(57) **CLAIM**

The ornamental design for an adaptor for rifle fired bullet trap grenades, as shown and described.

DESCRIPTION

The invention described and claimed herein may be manufactured, used, and licensed by or for the U.S. Government for U.S. Government purposes.

FIG. 1 is a perspective view of an adaptor for rifle fired bullet trap grenades of our new design.

FIG. 2 is a rear elevation view thereof;

FIG. 3 is a front elevation view thereof;

FIG. 4. Is a side plan view thereof, the other side plan view being a mirror image thereof;

FIG. 5 is a top plan view thereof; and,

FIG. 6 is a bottom plan view thereof.

Parts of the subject design in FIGS. 1, 2, and 3, are shown in broken lines for illustrative purposes only and form no part of the claimed design.
